DESIGN FOR A CANDELABRUM

Abraham Kessler, New York, N. Y.

Application January 10, 1941, Serial No. 97,949

Term of patent 3½ years

To all whom it may concern:

Be it known that I, Abraham Kessler, a citizen of the United States, residing at No. 55 Norfolk Street, in the city, county, and State of New York, have invented a new, original, and ornamental Design for a Candelabrum, of which the following is a specification, reference being had to the accompanying drawing forming a part thereof.

Fig. 1 is a front elevational view of a candelabrum showing my new design.

Fig. 2 is a side view thereof.

I claim:

The ornamental design for a candelabrum, substantially as shown.

ABRAHAM KESSLER.
